FOREIGN PATENT DOCUMENTS

GB 2 251 423 A 7/1992

Primary Examiner—Ian Simmons

(74) Attorney, Agent, or Firm—TraskBritt

(57) **CLAIM**

The ornamental design for a waste collection container, as shown and described.

DESCRIPTION

FIG. 1 is a top view of the waste collection container showing our new design;

FIG. 2 is a right perspective view of the waste collection container thereof;

FIG. 3 is a bottom view of the waste collection container thereof;

FIG. 4 is a side view of the waste collection container, the opposite view being a mirror image of that shown;

FIG. 5 is a front elevational view of the waste collection container, the rear elevational view being a mirror image of that shown;

FIG. 6 is a left perspective view of the waste collection container; and,

FIG. 7 is a rear perspective view of the waste collection container.

UNITED STATES PATENT AND TRADEMARK OFFICE
CERTIFICATE OF CORRECTION

PATENT NO. : Des. 502,993 S

Page 1 of 1

APPLICATION NO. : 29/153624

DATED : March 15, 2005

INVENTOR(S) : Greg McArthur, Fred P. Lampropoulos and Arlin D. Nelson

It is certified that error appears in the above-identified patent and that said Letters Patent is hereby corrected as shown below:

On the title page:

In the section (57) **CLAIM:**

change “The ornamental design for a waste collection container, as shown and described.” to
-- The ornamental design for a waste collection container as shown and described.--

In the section (57) **DESCRIPTION:**

change “FIG. 6 is a left perspective view of the waste collection container; and,” to
-- FIG. 6 is a left perspective view of the waste collection container; and--

Signed and Sealed this

Twenty-ninth Day of May, 2007

A handwritten signature in black ink, appearing to read "Jon W. Dudas", is centered within a rectangular dotted box.
